POCKET LIGHTER

Henry Gujer, Reinach, Switzerland, assignor to Metall-waren A.G. Birrwil, Birrwil, Switzerland, a Swiss corporation

Filed Dec. 24, 1968, Ser. No. 15,100

Claims priority, application Switzerland Oct. 9, 1968

Term of patent 14 years

Int. Cl. D27—05

U.S. Cl. D48—27

FIG. 1

FIG. 2

FIG. 3

FIG. 4

FIG. 5

FIG. 6

The undisclosed remaining side of the pocket lighter is identical to the side shown in FIGURE 2.

I claim:

The ornamental design for a pocket lighter, substantially as shown and described.
